Martin Briggs

Design for bastion fence

Patented Octo. 5. 1858.

Wm. F. McCoy
A. S. Brantley

Martin Briggs

Des. 1053

Martin Briggs, of Rochester, N.Y.
Letters Patent No. 1053, Dated Oct. 5, 1858.

The schedule referred to in these Letters Patent and making part of the same.

To all whom it may concern:

Be it Known that I, Martin Briggs, of the City of Rochester, County of Monroe & State of New York, have made certain improvements in the style & finish of Cast Iron Fences, Balconies &c, of which the following is a full and accurate description, reference being had to the accompanying drawings,

same letters referring to like parts in all the figures of said drawings.

Fig. 1. is an elevation of my improved pattern for Fence, Balconies &c.

Fig. 2. is a section at A.A.

Fig. 3. a section at B.B.

The nature of my improvement consists in the arrangements of the ornaments; such as the leaves, scrolls, & ropes as seen in the drawings and more fully understood from a detailed description. A.A. are the bars or uprights which are fastened to a top rail of wrought or cast iron (not represented) at C.

B.B. is the bottom rail to which the bars A.A. are fastened.

F.F. is the feet or lower part of the Fence or Balcony.

D. is an ornament in relief representing a rope running lengthwise of the bars A.A. rails B.B. & feet F.F. - I.I. are leaves passing over the rope C. a series of scrolls & leaves connecting the bars A.A. at the top.

The bars A.A. may be used with a wrought iron top & bottom rail or in combination with the bottom rail B.B. & feet F.F.

What I claim as my improvement and desire to secure by Letters patent is the arrangement of the rope ornament D.D. leaves I.I. and scrolls and leaves C. substantially as represented in the accompanying drawings. *End*
Witnesses.
